a corporation of Delaware

Application November 29, 1949, Serial No. 130,037

4 Claims. (Cl. 235—60.31)

1

This invention relates to accounting machines, and more particularly to means for preventing an uncontrolled movement of the type bars thereof, during a total taking operation of the machine.

The principal object of the present invention is to provide means for retaining the type bars in their total printing positions until they are engaged by the type bar restoring devices provided in the machine for restoration to their normal inoperative position.

Another object is to devise a means to prevent an uncontrolled jump of the type bars when, during a total taking operation, the register is disengaged from the type bars.

A further object is to provide a type bar retaining device which is operative only during cycles in which the type bars may be released to rise uncontrolled to their highest printing position.

Still another object is to provide a simple and inexpensive device to prevent an upward propulsion of the type bars during a total cycle with consequent noise and machine vibration and the possibility of erroneous machine functioning.

With these and other objects in view the invention consists in certain novel features of construction and combination of parts, the important elements of which are herein set forth in a preferred embodiment hereinafter described with reference to the drawings accompanying and forming part of this description.

In the drawings:

Figure 1 is a left side elevation of an accounting machine embodying the present invention showing the parts thereof occupying their normal position.

Figure 2 is a front elevation showing principally the parts embodied in the present invention in their normal position.

Figure 3 is a fragmental front view showing certain of the parts seen in Figures 1 and 2.

Figure 4 is a left side elevation showing the parts comprising the present invention in the positions they assume immediately after the machine has started its return stroke during an item entering operation of the machine, and

Figure 5 is a view similar to Figure 4 showing the parts in the positions they assume immediately after the machine has started its return stroke during a total taking operation of the machine.

The invention is described herein as embodied in the well known Sundstrand Accounting Machine disclosed in Patent No. 2,194,270 issued to

Oscar J. Sundstrand on March 19, 1940, and in Patent No. 2,209,240, issued to Oscar J. Sundstrand on July 23, 1940, to which reference may be had for details of construction not fully described and illustrated herein.

2

General Description

The machine includes generally a plurality of type bars ranging in number from nine to thirteen, employed for computing and printing numerical values, which are raised by lift springs to printing position during the first part of a machine cycle and are lowered to normal position against the tension of the springs during the latter part of the machine cycle by a conventional motor-drive mechanism. The type bars carry adding and subtracting racks which cooperate with upper and lower crossfooters and the type bars are connected to actuate adding racks which cooperate with an upper and lower group of four registers each, all of the crossfooters and registers being provided with transfer devices for effecting the transfer of an amount from one order to another. The machine includes a travelling paper carriage arranged to actuate controls for conditioning the machine to effect either item entering or total taking operations automatically and also includes a key-board for controlling the printing positions of the type bars for item entering operations and for manually controlling total taking operations of the machine. Also included in the machine is a mechanism for equalizing the load upon the motor drive. This load equalizing mechanism cooperates with the structure of the present invention and is described and illustrated in applicant's patent application, Serial No. 35,039, filed June 24, 1948, now U. S. Patent No. 2,493,799, issued January 10, 1950.

Detail description

Referring to Figure 1 of the drawings, the type bars 10 are suitably guided for vertical movement on a square shaft 11 rigid in the upper machine frame members 12, Figure 2, fixed to the machine base 13. Rigidly secured to the lower end of each type bar 10 is a slotted member 14 engaging a stud 15 in a type bar lifting lever 16 pivoted on a shaft 17. Strong springs 18, stretched between the lever 16 and the machine frame urge the type bars 10 upwardly to selectively position one type of the group of type 19 in position to print a selected numeral on a work sheet supported by a cylindrical platen

20 in a travelling paper carriage indicated generally at 21.

Connected at 22, Figures 4 and 5, to the slotted member 14 is a depending type bar extension 23 to which is affixed a slotted member 24 similar to member 14 which engages a stud 25 in a lifting lever 26 pivoted on a shaft 27 fixed in lower frame members 28 and 28a attached to the machine base 13. Strong springs 29 between the levers 26 and the frame members 28 and 28a cooperate with the springs 18 in raising the type bars 10 to printing positions. The type bars 10 and their extensions 23 are each provided with extending arms 30 supporting adding racks 31 and subtracting racks 32 cooperating with the associated crossfooter adding wheels 33 and 34. Each of the adding wheels 33 and 34 is provided with lugs 35 cooperating with transfer members 36 and 37 for transferring amounts from one order to another during item entering operations and for arresting the rotation of the register wheels during total taking cycles as described in the aforementioned Sundstrand Patent 2,209,240.

Pivoted on the shafts 17 and 27 are two groups of levers 38 each lever carrying a stud 40 engaging in a slot 41 in adding racks 42 and 43 for the register adding wheels 44 and 45 respectively.

The levers 38 are connected to levers 16 and 26 by a stud 39 on lever 38 engaging in an enlarged notch in the rear ends of levers 16 and 26 and by springs 46 which yieldingly urge levers 38 to raise the adding racks 42 and 43 for tens transfer purposes as described in the above Sundstrand Patent 2,209,240. Each of the register adding wheels 44 and 45 is provided with a lug 47 cooperating with a lug 48 of a transfer slide 49, mounted for vertical movement between the adding racks 42 or 43 and normally tensioned downwardly by springs 50. The transfer slides 49 are normally positioned with their lugs 48 opposite the shafts of the adding wheels 44 and 45 and in that position a shoulder 56 of slide 49 engages an ear 53 formed on the end of a transfer lever. Levers 51 are pivotally supported on a shaft 52 and are tensioned clockwise as in Figure 1 by individual springs 55. Each lever 51 is provided with a formed ear 57 overlying a lug 58 forming part of the associated rack 42 or 43, to normally retain the racks 42 or 43 at their zero position, and in position to effect transfer from one register order to another.

The machine is actuated by an electric motor (not shown), which is started by the closing of a suitable switch mechanism and is coupled with a cyclically operated actuating shaft 59 by a suitable clutch mechanism upon depression of a motor bar in the keyboard (not shown). The actuating shaft 59 is connected, by means of a lever 60 and link 61, with the motor drive in such manner that the shaft is rocked first clockwise and then counter-clockwise through an arc of about 90° during each operation of the machine. Rigid on the actuating shaft 59 are spaced arms 62 carrying rollers 63 bearing on spaced identical cams 64 pivoted on the shaft 17. Extending between the spaced identical cams 64 is a bar 65 overlying the forward arms of the type bar lifting members 16 and normally restraining the type bars 10 in their lowered position.

A second bar 67 carried between two cams 68 pivoted on lower shaft 27 overlies the forward ends of levers 26 and is connected to bar 65 by a pair of depending links 66 to assist in restoring

the type bars 10 to and restraining them in their lowered positions.

The rise of the type bars 10 during an item entering operation is differentially arrested by means of stops 69 which may be selectively projected by means of a keyboard (not shown) into the path of vertical movement of rods 70 connected to tails 71 pivoted on the type bars 10.

Normally, the crossfooter adding wheels 33 and 34 remain engaged with their associated racks 31 or 32 at the completion of a machine operation. The register adding wheels 44 and 45 which are selected for entry in the machine operation remain engaged with their associated racks 42 or 43 while the non-selected registers remain disengaged.

During an item entering operation of the machine, as the actuating shaft 59 is rocked clockwise the rollers 63, bearing on the edge 72 of the cams 64, retain the cams 64 and 68 and hence the type bars 10 in their lowered positions until any engaged register wheels 33, 34, 44 and 45 are disengaged from their associated racks. Upon contact of the rollers 63 with the upper edges 14 of the cams 64, the cams 64 are rocked upwardly about their pivot 17, raising the bars 65 and 67. As the bars 65 and 67 rise, the type bars, urged by the springs 18 and 29, rise with them until the rods 70 abut the key set stops 69, which for the highest elevation of the bars occurs slightly before the actuating shaft 59 reaches the end of its clockwise movement.

To insure perfect alignment of the type bars 10 in printing position, a type aligner 75 is pivotally supported on a shaft 76 rigid in the machine frame members 12. The type aligner comprises a blade 77 for engagement with notches 78 provided in the type bars 10. Aligner 75 is urged counterclockwise by a spring 79 and is under the control of a cam 80 forming part of one of the arms 62 as shown in Sundstrand Patent No. 2,194,270, issued March 19, 1940, the aligner being part 321 shown in Figure 34 of said patent. Near the end of the clockwise movement of actuating shaft 59 and after all type bars 10 have been positioned, the type aligner 75 is released to engage with its blade 77 the notch 78 in each of the type bars 10 which is positioned to the rear of blade 77 to depress all of the type bars slightly and align the type 10 in printing position and the teeth in the racks 31, 32, 42 or 43 for engagement by the adding wheels 33, 34, 44 or 45. The engagement of the type aligner 75 is followed immediately by the release of the hammers 81, pivoted at 82 and urged by springs 83, to strike the type 10 and cause printing of the set up number on the work sheet. At the start of the return stroke of shaft 59, the hammers 81 are restored, any selected adding wheels are engaged with their associated racks, and the type aligner 75 is returned to its normal position, as shown in Figure 1. The type bars are thereafter restored to their normal or lowered position by the bars 65 and 67 to add or subtract the amount in the crossfooter or to add it in the selected register. It is to be noted that the adding wheels 33, 34, 44 or 45 remain engaged with their associated racks to the end of the machine cycle.

During a total taking operation however, the selected adding wheels 33, 34, 44 or 45 are not disengaged from their racks and remain engaged with the racks during the forward or clockwise movement of the actuating shaft 59 whereupon the racks rotate the adding wheels during the

rising of the type bars, until a lug 35 in the cross-footer adding wheels 33 or 34, or the lug 47 in the register adding wheels 44 or 45 abuts its respective transfer member 36, 37 or 49, to arrest the rise of the type bars 10. As in the case of item entering, the type aligner 75 is released to engage the notch 78 in the type bars 10, and the hammers 81 are released to print the amount set up by the engaged crossfooter or register. Following the printing of the amount, the adding wheels are disengaged from their associated racks in order that they may be retained in their zero position, the hammers 81 are restored to a position clear of the type 19, and the type aligner 75 is disengaged from the notches 78 in the type bars 10 so that the type bars may be freely returned to their normal lowered position by means of the bars 65 and 67.

Since normally these machines are provided with a bank of nine to thirteen type bars, it can be readily seen that ordinarily only a few of the bars are utilized during item entering and only on rare occasions are the full number utilized for total printing. During item entering operations, therefore, the type bars 10 not used for printing are retained substantially in their normal lowered position by the abutment of their rods 70 with the underside of a locking plate 84. During total taking operations the locking plate 84 is withdrawn from its position overlying the rods 70 in a manner to be later described, leaving all of the type bars 10 free to rise upon the disengagement of the type aligner 75 from the notches 78 in the type bars and disengagement of the register wheels from their racks. In the prior machines, due to the urge of the springs 18 and 29 to raise the type bars, upon the disengagement of the type aligner and engaged adding wheels, the type bars were propelled upwardly at a high speed, until they struck the downwardly moving bars 65 and 67. Upon impact of the rising bars and the downwardly moving bars 65 and 67, a vibration was transmitted through the arms of the type bar lifting members 16 and 26 to their supporting shafts 17 and 27, through the machine base 13 and the register frame members 85 to the transfer members 49, causing those members to vibrate vertically between their supporting members 85. The extent and duration of the vibration varied with the force of the impact so that with the heavier blows, the vertical vibration of transfer members 49 was sometimes sufficient to raise shoulder 56 above the ear 53 of lever 51. This allowed lever 51 to cam member 59 upwardly and would in some types of operations cause a misoperation of the machine. Also, the impact of the type bar levers 16 and 26 with bars 65 and 67 tended to loosen the studs 15 and 26 and to cause excessive wear on shafts 17 and 27.

The present invention provides a means to prevent the upward movement of the type bars 10 by the springs 18 and 29 after a total taking operation which means is inoperable during item entering operations and is effective during total taking operations of the machine. This means comprises, Figures 4 and 5, a bracket 87 which is rigidly secured to the machine frame 28 and 28a in front of the type bars 10, a central portion 87a of the bracket serving to guide the lower end of the type bars 10. A shaft 88 is fixed between the end plates of bracket 87 and pivotally supports a yoke 89. A square stud 90 secured in an arm of yoke 89 is normally engaged in

notch 91 of a latch member 92 pivoted at 93 in the bracket 87 and tensioned into engagement with stud 90 by a spring 94 stretched between latch 92 and a rod 95 fixed in the bracket 87. Pivoted on shaft 38 and spaced apart by collars 96, see also Figure 2, are a plurality of depending detent pawls 97 retained in alignment with the type bar extensions 23 by means of set screw collars 98, Figure 2, and tensioned by individual springs 100 between their front ends and rod 95 to normally bear against a shaft 99 secured in yoke 89. Each of the type bar extensions 23 is provided with a plurality of notches 101 positioned therein in direct relation with the notches 78 for receiving the type bar aligner 75, the type 19 and the pawls 97. Slidably connected to latching member 92 by means of a stud 102 in the member and slot 103 is a link 104, the link 104 being pivoted at 105 to a bracket 106 secured to the type bar aligner 75. Pawl 97 are normally restrained from engagement with the type bar extensions 23 by the shaft 99 of yoke 89 since the yoke is latched in its counter-clockwise position by latching member 92.

During cycling of the machine for either item entering or total taking, and upon release of the type bar aligner 75 by the cam 80 for engagement with the notches 78 in the type bars 10, the latching member 92 is rocked upwardly about its pivot 93 by the raising of the link 104 by the bracket 106. The square stud 90 in the yoke 89 is thereby released to move toward engagement with a second notch 107 in latching member 92 under the urge of the springs 100 acting through the pawls 97 against the shaft 99.

During item entering operations of the machine, the engagement of the pawls 97 and notches 101 would be useless since the type bars 10 are prevented from upward unrestrained movement by the engagement of their rods 70 with the set pins 69 and plate 84. To prevent such engagement with the resultant wear, provision is made to permit full release of the detents 97 only during total taking cycles.

To this end a member 108 provided with slots 109 is mounted for vertical slidable movement on studs 110 of a bracket 111 secured on the machine frame 28 at 112, Figure 2, and to a fixed type bar guide comb 113, at 114. The lower end 115 of the member 108 is forwardly extended to normally lie to the rear of and in the path of movement of shaft 99 of the yoke 89, as shown in Figures 1 and 4, so that upon the release of the stud 90 by the latching member 92, as the result of the movement of the type aligner 75 into the notches 78 in the type bar, the yoke 89 and pawls 97 are rocked by the springs 100 until the shaft 99 abuts the extension 115 of the member 108, to hold the pawls 97 just short of engagement with the notches 101 in the type bar extensions 23, as is illustrated in Figure 4. While in this position the type bars 10 and their extension 23 are easily lowered by the bars 65 and 67 to add or subtract an amount in the adding wheels 33, 34, 44 or 45.

During the taking of a total from either of the crossfooters or registers, the member 108 is raised to clear the shaft 99 and permit engagement of the pawls 97 and the notches 101 when yoke 89 is released by operation of the type aligner 75. A total may be printed from a crossfooter or a register by forward movement of slides 120 and 121, Figure 2, respectively. These slides are moved either automatically under con-

trol of the carriage 21 through push rods 116, 117, Figure 1, and bell cranks 118 pivoted on shaft 119 or manually by control keys on the keyboard (not shown), as more fully set forth principally in Figure 27 and the description pertaining thereto in the above noted Sundstrand Patent No. 2,194,270. Each of the total control slides 120 and 121 is provided with a depending lug 122, Figure 2, which during the forward movement of the slides, moves levers 123 and 124 clockwise about their common pivot 125 in the machine base 13. Mounted in a frame 126 supporting the stops 69, Figures 1 and 2, is a shaft 127 on which is pivoted a yoke 128 connected at 129, Figure 1, with the lock plate 84 and provided with a depending arm 130. During the forward movement of the slides 120 and 121 and the consequent pivoting of the levers 123 and 124, the lever 123 strikes the depending member 130 to pivot the yoke 128 clockwise, as seen in Figure 1, and withdraw the lock plate 84 from its position overlying the rods 79 to enable the type bars 10 to rise freely to their total printing positions. The lever 124 is connected by means of a link 131 with a lever 132, pivoted at 133 on the machine base 13, and carrying a pin 134. Pivotally supported at 135 on the lower frame member 28a is a bell crank 136 having a slotted end embracing a stud 137 in the vertically slidable member 108 and provided with a slot 138, Figure 1, embracing the pin 134 in the lever 132. A spring 139, Figure 1, normally tensions the bell crank 136 counter-clockwise to hold the member 108 in position to block the movement of the shaft 99 as shown in Figure 1. Upon the pivoting of the lever 124, during the forward movement of the slides 120 and 121, the lever 132 is rotated in the opposite direction, to rock the bell crank 136 clockwise against the urge of the spring 139 and raise the member 108 to its upper position with the extension 115 thereof above and out of the path of movement of the shaft 99 of the yoke 89, as shown in Figure 5. With the member 108 so raised, the release of the type aligner 75 to engagement with the notches 78 in the type bars 10 and the consequent raising of the latch member 92 by the link 104, frees the yoke 89 which is rocked by the springs 100 until the square stud 90 abuts the second notch 97 in the latch member 92 and the pawls 97 engage the notches 101 in the type bar extensions 23. To insure simultaneous movement of the levers 123 and 124 upon the forward movement of either of the slides 120 and 121 they are tied together by means of a stud 140, Figure 2, rigid in the lever 124.

After printing of the total, the pawls 97 retain the type bars 10 in the positions assumed for printing the total until the type bars 10 are engaged by the bars 65 and 67 for restoration to their normal or lowered position. Due to the stud 102 and slot 103 connection between latch member 92 and the link 104, the retention of latch member 92 in its upper position does not prevent the usual disengaging movement of the type aligner 75 shortly after the start of the return of shaft 59. During the return of the type bars 10 to their normal or lowered position, the pawls 97 ride idly over the notches 101 in the type bar extensions 23.

During the lowering of the type bars 10 by the bars 65 and 67, and approximately at the time of their return to the zero printing position, the pawls 97 are disengaged from the notches 101 and returned to their normal position as shown in Figure 1. This is accomplished by utilizing

7
the movement of a slide 141 comprising a part of the load equalizing mechanism previously referred to. The slide 141 is connected at 142 to a swinging lever 143 pivoted at 144 on the machine frame 28a. A roller 145 on the lever 143 engages cam edges 146 and 147 of the cam 68. The slide 141 extends forwardly of the machine and is tensioned into engagement with a roller 148, supported in the machine frame 28a, by means of a spring 149. During the early part of the clockwise stroke of the shaft 59 the cam 68 is rocked about its pivot 27 by the bar 67 causing the cam edge 146 of cam 68 to move the slide 141 rearwardly of the machine, the cam edge 147 thereafter retaining the slide 141 in its rearward position until the latter part of the counter-clockwise stroke of the main shaft 59.

Near the end of the return stroke of cam 68, slide 141 is moved forwardly by the combined action of cam 68 and the camming action of spring 149 and roller 148 to engage an ear 150 on the lower arm of yoke 89, see Figure 3. Such engagement restores the yoke 89 to its normal position permitting the latch 92 to be pulled by its spring 94 to a lower position with its shoulder 91 in front of stud 90 to retain yoke 89 in restored position. During such restoration of yoke 89, shaft 99 thereon engages the lower arms of all the detents 97 and moves them to their ineffective positions out of engagement with the type bar extensions 23. Slide 141, previously released by the restoration of total control slide 120 or 121, drops to its blocking position in front of shaft 99 when the shaft is moved from under the extension 115.

The pawls 97 are thus released during the second half of a total cycle to engage the lower ends of the type bars 10 to prevent an unrestrained rise of the type bars and are returned to their normal ineffective position at the end of that cycle. During other cycles of machine operation, pawls 97 are retained in their ineffective positions throughout the entire cycle, thus reducing noise and wear on the parts.

Many variations are possible in constructional details without any departure from the spirit of the present invention. The disclosure is of a preferred embodiment only and is not to be taken as limiting the scope of invention which is defined in the appended claims.

50. What is claimed is:

1. In a machine of the class described, a plurality of differentially positionable type bars, cyclically operable means to yieldingly advance and positively retract said type bars, manually settable stop means to differentially arrest the advance of said type bars, a register, total control means operable to enable said register to differentially arrest the advance of said type bars, a plurality of detent pawls, yielding means to move said detent pawls into engagement with said type bars to prevent further advance of said type bars, a normally latched bail restraining said detent pawls from such engagement, aligning means for said type bars, a member operated by said aligning means to unlatch said bail, blocking means to arrest said bail prior to engagement of said detent pawls and said type bars, and connections between said total control means and said blocking means to withdraw said blocking means upon movement of said total control means.

2. In a machine of the class described having a plurality of differentially movable type bars, a register, movable register actuators controlled by

said type bars, cyclically operable means to control the advance and return of said type bars, indexable means to differentially arrest said type bars in their advancing movement, and function control means to determine engagement of said register with said register actuators to arrest an advance movement of said type bars in a total representing position, the combination of a plurality of detents to prevent movement of said type bars in an advancing direction, a bail engaging 10 said detents, a latch retaining said bail in a position to hold said detents away from said type bars, cyclically operated latch release means to withdraw said latch for a short interval, members urging said detents into engagement with said 15 type bars, a stop engageable with said bail to arrest movement of said detents before their engagement with said type bars, a linkage operable from said function control means to shift said stop to an ineffective position with respect to said bail and an arm driven by said cyclically operable means to return said bail and said detents to the latched position.

3. In an accounting machine of the class described having a plurality of type bars normally in a home position and differentially advanceable therefrom, settable indexing means to limit advance of said type bars, cyclically operating means to free said type bars for advancing movement from and to return them to the home position, a register, and function control means to determine engagement of said register with said type bars to limit the advancing movement thereof, the combination of a plurality of detents, each yieldingly urged into engagement with one of said type bars to prevent an advancing movement of said type bar, a bail engaging all of said detents, a cyclically operated arm connected to said cyclically operating means and effective to hold said bail and to thereby hold said detents in a non-engaging position while said type bars are in said home position, a latch for said bail, means to release said latch after said type bars have reached their differentially advanced positions, a stop to arrest said bail prior to engagement of said detents and said type bars, and a connecting means between said stop and said

function control means to move said stop to an ineffective position upon operation of said function control means.

4. In an accounting machine of the class described, a register, a plurality of register actuators, means resiliently urging said actuators from a home position, a power operated member engaging said register actuators and cyclically operated to free said actuators for advance from and to restore them to the home position, function control means to determine engagement of said register with said register actuators prior to advancing movement of said actuators to limit movement of the actuators to a total representing position and to disengage said register prior to return of said actuators to their home position, a plurality of detents, one for each register actuator and engageable with said actuators, a pivotal bail engaging all of said detents and normally holding them in ineffective position, and means to release said bail and permit engagement of said detents with said actuators comprising an arm driven by said power operated member to hold said bail in the detent disengaging position so long as said register actuators are in the home position, a latch cyclically operated while said actuators are in a most advanced position and a stop member shiftable to an ineffective position by said function control means upon operation thereof.
